CLAIM

The ornamental design for a flower stand, as shown and described.

DESCRIPTION

FIG. 1 is a top perspective view of a flower stand showing my new design the broken line showing in FIG. 1 being for illustration purposes only;

FIG. 2 is an enlarged right side elevational view, the left side being a mirror image thereof;

FIG. 3 is an enlarged top plan view thereof;

FIG. 4 is an enlarged front elevational view thereof;

FIG. 5 is an enlarged bottom plan view thereof; and

FIG. 6 is an enlarged fragmentary rear elevational view wherein the upper portion has been omitted for convenience of illustration.

FIG. 1

FIG. 2

FIG. 3

FIG. 4

FIG. 5

FIG. 6
